CLAIM

The ornamental design for a warning light housing for emergency vehicles, as shown and described.

DESCRIPTION

FIG. 1 is a front elevational view of the warning light housing for emergency vehicles showing our new design, the rear elevational view being the mirror image of the front elevational view;

FIG. 2 is a top plan view thereof;

FIG. 3 is a bottom plan view thereof;

FIG. 4 is a left side elevational view thereof, the right side elevational view being the mirror image of the left side elevational view; and,

FIG. 5 is a perspective view taken from the front, left and top of the warning light housing for emergency vehicles.
